UNITED STATES PATENT OFFICE.

WILLIAM P. BREWSTER, OF ST. LOUIS, MISSOURI, ASSIGNOR OF ONE-HALF TO
BENJAMIN A. WILKES, OF ST. LOUIS, MISSOURI.

TIMING AND IGNITION SYSTEM.

Application filed August 9, 1921. Serial No. 490,991.

To all whom it may concern:

Be it known that I, WILLIAM P. BREWSTER, a citizen of the United States, residing at city of St. Louis, State of Missouri, have 5 invented a certain new and useful Improvement in Timing and Ignition Systems, of which the following is a full, clear, and exact description, such as will enable others skilled in the art to which it appertains to 10 make and use the same, reference being had to the accompanying drawings, forming part of this specification.

This invention relates to a timing and ignition system for internal combustion engines and the objects of my invention are 15 to provide a combined timing and ignition system which is simple and efficient in operation and may be advantageously used with internal combustion engines thereby eliminating the complicated and expensive timing mechanism now used in conjunction with ignition systems.

Further objects of my invention are to provide a combined timing and ignition 20 system in which the timing of the spark used to ignite the compressed charge of combustible gases in the combustion chamber is accomplished by the movement of the piston in said combustion chamber, said 25 piston actuating a movable electrode to establish an electric contact with an adjustable contact member whereby a spark is produced between said movable electrode and a stationary electrode, said contact 30 member being manually operable whereby the spark can be advanced or retarded.

Still further objects of my invention are to provide means controlled by the pressure 35 in the combustion chamber, said means being interposed in the ignition circuit so that said circuit remains open until said means are actuated by the pressure generated in the combustion chamber to operate said means and complete the ignition electric circuit.

Still further objects of my invention are to provide adjusting means whereby said timing and ignition system can be regulated to properly perform the intended functions.

With the foregoing and other objects in view my invention consists in certain novel features of construction and arrangement of parts hereinafter more fully described and

claimed and set forth in the accompanying drawings, in which,--

Figure 1 is a top view of the spark plug and its operating connections. 55

Figure 2 is a vertical cross section taken on the line 2--2 of Figure 1.

Figure 3 is a vertical cross section taken 60 on the line 3--3 of Figure 1.

Figure 4 is a horizontal cross section taken 65 on the line 4--4 of Figure 2.

Figure 5 is a vertical cross section taken 70 on the line 5--5 of Figure 1.

Figure 6 is a horizontal cross section taken 75 on the line 6--6 of Figure 5.

Figure 7 is a top view of a series of modified forms of plug and connections therefor.

Figure 8 is a vertical cross section taken 80 on the line 8--8 of Figure 7.

Figure 9 is a vertical cross section taken 85 on the line 9--9 of Figure 7.

Figure 10 is a horizontal section taken 90 on the line 10--10 of Figure 9.

Referring by numerals to the accompanying drawings, 10 indicates a spark plug, the lower end of which is threaded for engagement with an internally threaded seat formed in the cylinder head of an internal 80 combustion engine, said plug being provided with an axial opening 11 threaded at the upper end, as indicated at 12, and having a reduced lower end to form an annular seat 14. 85

Snugly fitting in this opening is a tubular insulator 15 and longitudinally disposed therein is a rod 16 which serves as one of the electrodes. The lower end of insulator tube 15 has a reduced annulus to form an 90 annular shoulder 15^a which is designed to rest upon the annular seat 14. The upper end of tube 15 which projects upwardly from plug 10 is of reduced diameter to form a circular shoulder or abutment 15^b against 95 which is designed to bear the threaded lower end of a tubular member 17. This tubular member is screw seated in the threaded upper end 12 of the opening 11 and holds tube 15 in position in plug 10. The upper end 100 of rod 16 extends upwardly past tubular member 17 and is threaded to receive binding screws 18 adapted to receive the one terminal of a high tension coil. The lower one of binding screws 18 rests on the upper 105 end of a cap piece 19 formed of insulating

material and bearing against the upper end of sleeve 17 thereby locking said sleeve in position.

If desired, suitable cement can be used to secure rod 16 in insulator tube 15 and the latter can be secured in position in plug 10 in a similar manner.

Longitudinally disposed in spark plug 10 and parallel with axial opening 11 is an opening 20 in which is arranged a rod 21 which acts as the other electrode. The upper portion of opening 20 is formed of larger diameter in order to accommodate a spring 22, the lower end of which bears against a collar 21^a formed on rod 21 and the upper end engages the lower end of a sleeve 23 which is slipped on rod 21. A cap 24, through which the upper end of said rod 21 projects, is removably held in position on the plug 10 and its lower end projects into opening 20, and cooperates with sleeve 23 to hold in position suitable packing material and thus prevent escape of gases through the upper end of opening 20. This upper end of rod 21 terminates a predetermined distance below a yielding member 25 carried by the arm 26 which is fixed to horizontally disposed rocking shaft 27, the latter being journaled in suitable bearings 28. An insulating block 29 is fixed in any suitable manner to the upper end of plug 10 and supports bearing 28 in position. The rocking shaft 27 can be rocked in its bearings by means of an arm 30 secured at one end to said shaft and having a connection 31 at its free end which connection extends towards the dash-board and is connected to any suitable means so that it can be manually operated.

The lower end of rod 21 extends downwardly past the lower end of plug 10 into the combustion chamber and is provided with a collar or abutment portion 32 designed to be engaged by the piston P during its upward movement, whereby said rod 21 is moved upwardly until its upper end 21^b engages and establishes electric contact with the yielding member 25.

Carried by the insulating block 29 and insulated from electrodes 16 and 21 is a contact member 34 having a binding screw 35. This contact member 34 is in the plane of movement of a plunger 36, the upper end of which projects outwardly from a housing 37 and is adapted during its outward movement to engage said contact member 34 and establish electric contact therewith. Plunger 36 is carried by piston 38 which is movably mounted in housing 37 and has a pin or projection 39 at its opposite end which is designed to bear against the respective end of said housing and thereby form a chamber 40 into which leads a port 41 formed in a nipple 37^a which is formed integral with 40 and projects transversely from the lower

end of housing 37. The end of nipple 37^a is threaded and engages a threaded opening or passage-way 42 formed in one side of plug 10 and extending longitudinally through the lower end of said plug so as to 70 form communication when the plug 10 is screwed in place in the cylinder head of the engine between the combustion chamber and chamber 40 of housing 37. The lower end of housing 37 is preferably closed 75 by a removable plug 44 and the upper end of said housing is closed by plug 45 which is apertured to accommodate the upper end of plunger 36. Interposed between plug 45 and piston 38 is an expansion spring 46 so which tends to hold plunger 36 out of engagement with contact member 34.

In the operation of my timing and ignition system, one terminal of a battery is connected to binding screw 35 and the opposite terminal is connected to the rocking shaft 27. Arm 30 is then operated to position yielding member 25 the proper distance from the upper end 21^b of rod 21. During the compression stroke of the piston of the engine, the pressure created by the compression of the combustible gases in the combustion chamber will be communicated through passage-way 42 to chamber 40 causing piston 38 to move upwardly against the influence of spring 46 and bring plunger 36 in contact with contact member 34; thus electrode 21 will be electrically connected to that terminal which is secured by binding screw 35. At the proper time, just before the completion of the compression stroke, piston P will engage the lower end of electrode 21 and move it upwardly so that its upper end 21^b will come in contact with member 25 so that the electric circuit 100 will be completed, the current traveling from binding screw 35 to plunger 36, then through housing 37 and plug 10 to electrode 21 and through member 25, arm 26, shaft 27, to the other terminal of the battery 110

Immediately upon contact of member 25 in the upper end 21^b in rod 21, a spark will be produced between the lower end of electrode 16 and the lower portion of rod 21 by a coil which is included in said battery 115 circuit and has one end of its high tension circuit connected to the binding screw 48 while the other end is grounded in the usual manner. As soon as the combustible charge has been fired by the spark, rod 21 will, 120 under influence of spring 22, move downwardly disconnecting its upper end 21^b from member 25. Piston 38 will return to its normal position under the influence of spring 46, thereby disengaging plunger 36 125 from contact member 34. During the exhaust stroke of the piston, said piston will operate electrode or rod 21 to engage member 25 but no spark will be produced in view of the fact that piston 38 has not been 130

moved to bring plunger 36 in engagement with contact member 34, said piston 38 being operable only by the pressure created by compressing the combustible gases.

- 5 Housing 37 is provided with a suitable aperture 37^b whereby oil can be introduced into said housing which aperture will serve also as a vent for connecting the upper portion of said housing with the atmosphere.
- 10 A similar opening 20^a is formed in the upper portion of plug 10 to permit admission of oil into opening 20 and is closed by a plug 20^b.

In the timing and ignition system just described, a separate coil has to be provided for each plug. In the modified form shown in Figures 7 to 10, a single coil is provided for a series of spark plugs, an auxiliary set of contacts being arranged for that purpose.

- 20 In the modified form, the plunger 36^a is threaded and provided with an insulating cap 47 having an outer metallic jacket 48. Engaging this metallic jacket or member 48 is contact 49 carried by the lower end of 25 rod 50 which passes upwardly through and is secured to the insulating block 29. A binding screw 51 is arranged on the projecting end of rod 50 and is designed to engage suitable electrical connection leading 30 from one terminal of the high tension circuit.

When the combustible gases are compressed in the combustion chamber, piston 38 is operated to raise plunger 36^a so that 35 metallic member 48 engages the contact 34, whereby electric connection is established between binding screws 35^a and 51 through 40 rod 50, contact arm 49, cap 48, and contact 34^a. Binding screw 35^a is electrically connected to a binding screw 18^a carried by the upper 45 end of electrode 16 and binding screw 51 has connected to it one terminal of the high tension circuit of the coil, the other terminal thereof being grounded to the engine in the usual manner. Thus when member 48 is moved into contact 34^a by the pressure in 50 combustion chamber operating piston 38, a spark will be produced between the electrodes 16 and 21. If desired, piston 38 can be provided with a piston ring 52 in order to form a fluid tight joint and prevent the escape of gases past said piston.

In Figures 1 to 6, plunger 36 controls the battery circuit, said circuit having interposed therein a coil in the usual manner. One of the terminals of said battery circuit is connected to binding screw 35^a while the other terminal is connected to rocking shaft 27 and one terminal of the high tension circuit of said coil is connected to binding screw 18, while the other is grounded to the engine. Thus the battery circuit is normally held open by plunger 36 and is closed when plunger 36 engages contact 34 and electrode 21 is moved into contact with member 25,

said electrode 21 and plunger 36 being electrically connected to each other by virtue of the fact that they are both mounted on the metallic plug 10, consequently a separate coil is required for each plug 10.

In Figures 7 to 10, one of the terminals of the battery circuit is grounded to the engine and the other terminal is connected to rocking shaft 27.

One terminal of the high tension circuit 75 of the coil, which coil is interposed in said battery circuit in the usual manner, is connected to binding screw 51, while the other terminal is grounded to the engine. Thus the battery circuit is controlled by the movable electrode 21 and the high tension circuit 80 is controlled by contact member 48 carried on the upper end of plunger 36^a.

To retard the spark, arm 30 is operated to move member 25 away from the upper end 85 21^b of the electrode 21, thereby increasing the space traversed by said electrode before said electrode establishes electrical contact with member 25. To advance the spark, arm 30 is operated to bring member 25 closer to the upper end 21^b and thus reduce the distance therebetween. Consequently the advancing or retarding of the spark, as well as the timing, is accomplished through the cooperation of electrode 21 and member 25 95 and the production of the spark is controlled through the cooperation of contacts 34 and 34^a with the pressure operated plungers 36 and 36^a.

A timing and ignition system constructed according to my invention is accurate and efficient in operation, the timing being accomplished by the movement of the piston while the electric circuit is controlled by the pressure created in the combustion chamber so that no ignition will take place except upon the compression of the combustible gases in the combustion chamber and where a series of combustion chambers is used, the ignition of each combustion chamber is controlled solely by the pressure in said combustion chamber and is not affected by the remaining combustion chambers.

I claim:

1. In a timing and ignition system for internal combustion engines, an ignition circuit, a pair of electrodes in said circuit, one of said electrodes being operable by the piston of said engine to complete said ignition circuit, and a contact member controlling said ignition circuit and operable by the pressure created by compression of the combustible gases in the combustion chamber of said engine.

2. In a timing and ignition system for internal combustion engines, an adjustable contact member, a pair of electrodes, one of which is operable by the piston of the engine to establish contact with said contact member, electrical connections between the

125

130

- adjustable contact member and the other one of said electrodes, and an auxiliary contact member for controlling said electrical connections and operable by pressure in the combustion chamber of said engine. 5
3. In a timing and ignition system for internal combustion engines, a stationary electrode, a movable electrode, a contact member adjustable relative to said movable electrode, said movable electrode being adapted to form electrical contact therewith in synchronism with the movement of the piston of said engine, the stationary contact member, and a movable contact member adapted to be actuated by the pressure in the combustion chamber of said engine to engage said stationary member whereby the electric circuit between said electrodes is completed. 10
4. In a timing and ignition system for internal combustion engines, an ignition circuit including a pair of electrodes one of which is adapted to be actuated by the piston of the engine with which said system is associated, and a contact member for controlling said circuit, said contact member being operable by the pressure generated by compressing the combustible gases in the combustion chamber of said engine. 15
5. In a timing and ignition system for internal combustion engines, an ignition circuit including a pair of electrodes one of which is adapted to be actuated by the piston of the engine with which said system is associated, a contact member adapted to form contact with said movable electrode and adjustable relative thereto, and an auxiliary contact member adapted to complete said ignition circuit when the combustible gases in the combustion chamber of said engine are compressed to a predetermined degree. 20
6. An electric igniter for internal combustion engines comprising a pair of electrodes, electrical connection therefor, adjustable contact means in said electrical connection, one of said electrodes being operable by the piston in the engine to electrically engage said adjustable means, normally disengaged contact members for controlling said electrical connections, a housing having communication with the combustion chamber of said engine, and means movably mounted in said housing and adapted to be actuated by 25
- the compression in said combustion chamber to engage said contact members whereby said electrodes become energized. 55
7. In a timing and ignition system for internal combustion engines, a plug adapted to be screw-seated in the cylinder head, a pair of electrodes arranged therein, an electric circuit for said electrodes, a housing fixed to said plug and communicating therethrough with the combustion chamber of said engine, a pair of contact members interposed in said circuit and mounted exteriorly on said housing, a piston movably mounted in said housing and operable by the pressure created in the combustion chamber by compressing the combustible gases, and a contact member carried by said piston and adapted when said piston is operated to engage said 60 contact members and close said circuit. 65
8. In a timing and ignition system for internal combustion engines, a plug adapted to have its lower end secured to the cylinder head of said engine, a pair of electrodes mounted therein, an electric circuit therefor, a housing supported exteriorly on said plug and having communication with the engine combustion chamber, a piston movably mounted in said housing, contact members 70 mounted on the upper end of said plug and interposed in said electric circuit and normally disengaged from each other, and means operable by said piston and adapted to interengage said contact members. 75
9. In an ignition system for internal combustion engines, an ignition circuit including a pair of electrodes, one of which is operable by the piston of said engine, and means interposed in said circuit and adapted to be 80 engaged by said movable electrode to complete said circuit. 85
10. In an ignition system for internal combustion engines, an ignition circuit including a pair of electrodes, one of which is operable by the piston of said engine, and means interposed in said circuit and adapted to be 90 engaged by said movable electrode to complete said circuit, said means being manually operable to advance or retard the spark. 95

In testimony whereof I hereunto affix my signature this 3rd day of August, 1921.

WILLIAM P. BREWSTER.
